UNITED STATES PATENT OFFICE.

MILTON PELKEY, OF MILWAUKEE, WISCONSIN.

LOCK BOLT.

Application filed August 2, 1926. Serial No. 126,558.

This invention relates to lock bolts, primarily applicable for use upon ties and in conjunction with rails seated thereon, embodying a sleeve member carried by the bolt 5 and adapted for expansion within a bore to insure rigid association of the bolt upon the tie.

An object of the invention is to provide anchoring plates upon which the feet of rails 10 are seated and adapted for association with the sleeve member and bolt and converging over the foot of a rail to hold the same against displacement.

With the above and other objects in view, 15 the invention further includes the following novel features and details of construction, to be hereinafter more fully described, illustrated in the accompanying drawing and pointed out in the appended claims.

20 In the drawings:

Figure 1 is a sectional view taken through a portion of a tie and rail and illustrating the manner by means of which the invention is associated therewith;

25 Figure 2 is a top plan view of the invention as applied, partly broken away to illustrate the construction thereof;

Figure 3 is a perspective of a combined seat and retaining plate;

30 Figures 4 and 5 are plan views of seat plates;

Figure 6 is a perspective view of the sleeve member;

Figure 7 is a similar view of the bolt.

35 Referring to the drawing in detail, wherein like characters of reference denote corresponding parts, the reference character 10 indicates a tie which may be constructed of any suitable material but in this instance, 40 a wooden tie is employed, for purposes of illustration only.

Said tie has spaced bores arranged therein, within which are received split sleeves 11, which include cutout portions 12 in the 45 upper periphery thereof, the purpose of which will be readily apparent. Positioned within the sleeves 11 are bolts 13 provided with tapered portions 14 upon one end in order that the upward travelling movement 50 of the bolt within the sleeves will expand the latter into the bores of the tie to rigidly anchor the bolts. Those portions of the sleeves between the splits thereof are corrugated, as indicated at 15. A plate member 55 16 is seated upon the upper surface of the

tie having cut-away larger and reduced portions 17 and 18 respectively. Within the reduced portion 18 is an inwardly extending finger 19 adapted for reception within the cutout portion 12 in the upper periphery 60 of the sleeve 11 to prevent the latter from becoming displaced. An additional plate 20 is provided with a tongue 21 upon one end, adapted for interfitting engagement with the larger portion 17 of the plate 16 and 65 upon the opposite side of the sleeve, to provide a seat for the foot 22 of a rail 23, substantially as illustrated in Figure 1 of the drawings.

Receiving the upper protruding end of the 70 bolt 13 is a plate 24 upon the upper surface of which is positioned a washer 25 and a nut 26 for regulating the anchorage of the bolt 13 upon the tie. One edge of such plate is bent upwardly and forwardly upon 75 itself to conform to the configuration of one side edge of a rail foot, as indicated at 27. The opposed portion of the foot is positioned between a correspondingly shaped portion 28 of a plate 29 which in addition provides correspondingly disposed legs 30 upon the 80 opposite sides thereof. The plate 29 is correspondingly anchored to the tie in order that the foot 22 of the rail 23 will be rigidly held against displacement. 85

As illustrated, the plates 16 and 20, as in the instance of the legs 30 of the plate 29, are fitted within cutout portions provided in the upper surface of the tie whereby the latter will provide an even seat for 90 the rail.

In the application of the invention the plates 16 and 20, as in the instance of the fingers 30 are disposed within the depressed or cutout portion in the upper surface of the tie 10. The portion 28, upon the setting of the legs 30 will engage the upper side of the rail foot 22. The plate 24 is then arranged flush with the upper surfaces of the plates 16 and 20 and receives the upper 95 extremities of the sleeve and bolt. Said plate 24 also includes a portion 27 adapted for engagement with the opposed side of a rail foot 22. A lock washer 25 and nut 26 are then received upon the upper end of 100 the respective bolts 13 to properly anchor the foot of the rail against displacement. 105

The invention is susceptible of various changes in its form, proportions and minor details of construction, and the right is here- 110

in reserved to make such changes as properly fall within the scope of the appended claims.

I claim:

1. A locking device comprising a bolt, a split sleeve carried by the bolt, seat and gripping plates connected with one end of the bolt, and means provided at an appropriate point in the length of the bolt to cause the expansion of the sleeve in the anchoring of the bolt.
2. A locking device for use upon rails comprising a bolt provided with a tapered portion adjacent one end, a split sleeve carried by the bolt, a seat plate receiving the upper protruding end of the bolt, and a securing plate arranged in superimposed relation upon the seat plate and engageable with the foot of a rail.
3. A locking device for use upon rails comprising a bolt provided with a tapered portion adjacent one end, a split sleeve carried by the bolt, a seat plate receiving the upper protruding end of the bolt, a securing plate arranged in superimposed relation upon the seat plate and engageable with the foot of a rail, and means provided in opposed relation to that of the securing plate to engage the opposite side of the rail.
4. A locking device comprising a bolt,

said bolt provided with a tapered portion 30 adjacent one end, a split sleeve carried by the bolt and including a cutout portion in the upper periphery thereof, a plate member having successive cutout portions upon one side edge, a finger therein adapted for engagement within the cutout portion in the periphery of the sleeve, a seat plate having a tongue upon one end adapted for interfitting engagement with the cutout portion of the aforementioned plate, a locking plate 40 arranged in superimposed relation upon the upper side of the first mentioned plate and including an upwardly and forwardly inclined portion conforming to the configuration of the side edge of a rail foot, and an additional plate member defining a correspondingly disposed portion upon its adjacent edge.

5. In a locking device a tapered portion carried upon one end thereof, a split sleeve 50 provided with corrugations upon one end and a cutout portion in the other, a seat plate providing a finger for reception within the cutout portion and means for expanding the split end of the sleeve.

In testimony whereof I affix my signature.

MILTON PELKEY.
